United States Patent Office

Des. 180,158
Patented Apr. 23, 1957

180,158

TELEVISION ANTENNA OR SIMILAR ARTICLE

Andrew J. Raftis, Harry J. Raftis, and Alexander J. Raftis,
Chicago, Ill.

Application July 19, 1956, Serial No. 42,304

Term of patent 14 years

(Cl. D26—14)

FIG. 1

FIG. 2

FIG. 3

Figure 1 is a front elevational view of a television antenna or similar article, showing our new design;
Figure 2 is a side elevational view thereof; and
Figure 3 is a top plan view thereof.
We claim:

The ornamental design for a television antenna or similar article, as shown.
